(57) **CLAIM**

The ornamental design for a bottle, as shown and described.

DESCRIPTION

FIG. 1 is a rear perspective view of a bottle, illustrating our new design;

FIG. 2 is a front view thereof;

FIG. 3 is a rear view thereof;

FIG. 4 is a left side view thereof;

FIG. 5 is a right side view thereof;

FIG. 6 is a top view thereof; and,

FIG. 7 is a bottom view thereof.

Broken lines are used in the drawings to illustrate features of the bottle that form no part of the claimed design. In FIG. 7, the dot-dot-dash line indicates a boundary of the claimed design, which also forms no part of the claimed design.
